ADJUSTABLE SUPPORT

Carl G. Oreich, New York, N. Y., and Edward G. Schaaf, Palisade, N. J.

Application February 2, 1940, Serial No. 316,952

1 Claim. (Cl. 224—5)

This invention relates to an improved adjustable support for musical instruments. More particularly the invention relates to an adjustable support comprising a strap to be worn around the neck of an instrument player, an attaching device to be connected to the instrument, a flexible cord connected between the strap and attaching device, and an adjustable slide through which the flexible cord is threaded and whereby the effective length of the cord may be varied.

It is an object of the invention to provide an improved adjustable member of the above character in which the flexible cord is readily detachable from the remaining portions of the device so as to be replaceable when it is worn out.

A further object is the provision in an adjustable support of an adjusting slide of an improved simplified and inexpensive construction which may be readily adjusted to vary the length of the support but which, when adjusted, will resist accidental displacement.

Another object is the provision of an improved assembly of adjusting slide and flexible cord whereby the slide can be shifted to readily adjust the effective length of the cord and wherein the ends of the cord are attached to the slide in an improved manner so that they can readily be released to permit replacement of the cord.

In the accompanying drawing—

Fig. 1 is a view of an adjustable support for a musical instrument embodying our invention;

Fig. 2 is an enlarged sectional view of the adjusting slides and of the adjacent portions of the flexible cord;

Fig. 3 is a sectional view in the direction of the arrows on the line 3—3 of Fig. 2;

Fig. 4 is a perspective view of the adjusting slide;

Fig. 5 is a sectional view in the direction of the arrows on the line 5—5 of Fig. 6 of a modified type of adjusting slide;

Fig. 6 is a sectional view in the direction of the arrows on the line 6—6 of Fig. 5 of the modified adjusting slide; and

Fig. 7 is a perspective view of the modified adjusting slide.

Our improved adjustable support comprises a strap 10 made of leather or some other suitable flexible material adapted to encircle the neck of the user, an attaching device such as the hook 11 which is adapted to be connected to a saxophone, bassoon or some other musical instrument, a flexible cord 12 made of braided or woven fabric or of leather or some other suitable

material and connected between the strap and the attaching device, and an adjusting slide 14 to which the cord is threaded so that the effective length thereof may be varied by shifting the 5 position of the slide.

The general shape and contour of the slide may be varied. However, in the preferred form of our invention as shown in the first four figures of the drawing the slide is generally oval 10 shape and is provided with three openings 15, 16 and 17 extending transversely through the slide in parallel relationship. Each of the openings is preferably of a size to rather snugly accommodate two strands of the cord 12. As 15 shown the openings 15 and 17 are positioned adjacent the lower and upper ends respectively of the slide while the opening 16 is positioned adjacent the central portion thereof. The two sides of the slide between the openings 16 and 17 are 20 preferably recessed as indicated at 18 to accommodate the cord.

The cord 12 is releasably connected to the several parts so that it may be replaced when desired. We attach the cord adjacent its central 25 portion to hook 11 and this attachment, while it is of a releasable character, may be fixed, that is, it need not provide for sliding or shifting of the cord relative to the hook. The connection preferably takes the form of a mooring knot 30 as shown at 19. Thus the central portion of the cord is formed into a loop which is projected through eye of hook 11 and the two strands 20 and 21 of the cord are then extended through the bight of the loop and the loop pulled tight. 35 Strands 20 and 21 are then extended in opposite directions through the opening 15 after which they are formed into loops which extend through apertures or eyelets 22 formed adjacent the two ends of strap 10. The strands are 40 then brought back to slide 14 and extended in opposite directions through aperture 17 and the end portions are projected into and anchored in aperture 16. So as to resist release of the end portions from the aperture 16 and thus releasably connect the ends of the strand to the slide 14 we have found that the ends should be rigid or 45 inflexible in character. For this purpose we preferably encase the ends in metal sheaths or tips as indicated at 23. It will be seen that when 50 the strands are pulled tight the cord between apertures 17 and 18 rests in the recessed portions 18. Due to the relatively sharp angle of the strands of the cord the encased ends 23 will resist accidental removal from aperture 16.

The effective length of the cord 12 between

strap 10 and hook 11 can be readily adjusted by shifting slide 14. When slide 14 is shifted towards the hook the effective length is reduced. When it is shifted away from the hook the effective length is increased. Due to the relatively sharp angles of the strands of the cord entering and leaving aperture 15 and due to the relatively close fit of the strands in aperture 15 accidental shifting of the slide is effectively prevented. Accidental shifting or disturbance of the adjustment is also prevented by the fact that the strands 20 and 21 of the cord must slide in opposite directions in opening 15 when the device is adjusted.

In using our improved adjustable support the strap 10 is placed around the neck of the user, hook 11 is attached to the saxophone, bassoon or other musical instrument and slide 14 is adjusted so that the cord is of the desired length. Once the adjustment is made the effective length of the cord will remain the same until the adjustment is changed.

In the modified form of our device shown in Figs. 5, 6 and 7 we employ the same type of strap, hook and cord. However, we use a modified type of slide as shown at 14' which may be made in various shapes and configurations. In the form illustrated the slide is generally rectangular in shape and is provided with a transverse aperture 24 and two parallel apertures 25 disposed at right angles to the aperture 24 and horizontally offset with respect to that aperture. The apertures, particularly the aperture 24, are preferably of a size to rather tightly accommodate two strands of the cord 12. In the modified form of slide the central portion of cord 12 is attached to hook 11 in the same manner as shown in Fig. 1. The strands 20 and 21 are then extended upwardly and through aperture 24 in opposite directions. After leaving aperture 24 the two strands are extended through apertures 22, formed into loops, and brought back to the slide 14' where they are releasably attached thereto by extending each of the strands through one of the apertures 25 and then projecting the metal encased end 23 thereof up-

wardly into the other slide 25. As in the first form of slide the sharp angle causes the metal encased end to resist accidental release even when strong pressure is applied to the device.

5 The modified form of our invention is utilized in the same manner as the first form of our invention. The effective length of cord 12 may be shortened and lengthened by shifting the slide 14' towards and away from hook 11.

10 It will thus be seen that we have provided an improved adjustable support for musical instruments or the like which is of simple and inexpensive construction, which provides for the ready replacement of the flexible cord and which may readily be adjusted to the desired length. It should be understood of course that modifications may be made in the illustrated and described embodiment of our invention without departing from the invention as set forth in the accompanying claim.

15 We claim:

20 In an adjustable support for musical instruments having a strap formed with apertures adjacent its two ends adapted to encircle the neck of the wearer and an attaching device for attaching the support to a musical instrument, the combination of a unitary flexible cord having inflexible tipped ends and an adjusting slide having three substantially parallel transversely 25 extending apertures, the flexible cord being connected adjacent its central portion to the attaching device with the two strands extending from the connected portion extending through the lowermost aperture in the slide in opposite directions and thence being formed into loops extending through the apertures in the strap, the said strands adjacent the inflexible tipped ends being projected through the uppermost aperture in opposite directions with the inflexible tipped 30 ends positioned in the intermediate apertures whereby the slide may be shifted to adjust the effective length of the cord and the ends of the cord are releasably connected to the slide.
